UNITED STATES PATENT OFFICE.

HARRY PHILIP THATCHER, OF BEVERLY, AND JOSEPH W. HANLEY, OF FALMOUTH, MASSACHUSETTS.

CARBURETER.

1,354,583.

Specification of Letters Patent.

Patented Oct. 5, 1920.

Application filed April 17, 1917. Serial No. 162,639.

To all whom it may concern:

Be it known that we, HARRY P. THATCHER and JOSEPH W. HANLEY, citizens of the United States, residing, respectively, at Beverly, in the county of Essex and State of Massachusetts, and Falmouth, in the county of Barnstable and State of Massachusetts, have invented certain new and useful Improvements in Carbureters, of which the

10 following is a specification.

Our invention relates to carbureters for internal combustion engines and the object thereof is to provide an improved carbureter that is particularly adapted to use the 15 heavier hydro-carbons such as kerosene.

In accordance with our invention the carbureter is provided with a chamber or retort that is preferably a tube extending through the exhaust manifold of the engine to which 20 the carbureter is applied, said chamber having an outlet connected with the intake of the engine cylinder or cylinders and an inlet connected with a supply of relatively heavy hydro-carbon such as kerosene as well 25 as an air inlet, all constructed and arranged so that both kerosene and air in definite and regulated proportions such as to complete the explosive mixture are drawn into said chamber by the suction strokes of the engine 30 pistons, or piston, and pass through said chamber into the cylinder or cylinders. Preferably the two inlets of the exhaust heated chamber are arranged at one end of the chamber and the outlet of said chamber 35 at the opposite end of the latter so that the kerosene is thoroughly vaporized and mixed with the air and both are heated in passing through the chamber to the outlet of the latter. Our improved carbureter may be used 40 with another carbureter for a lighter hydro-carbon such as gasolene, said latter carbureter being also connected with the intake of the engine as usual. This provides for starting the engine on gasolene and running it 45 on the latter until the mixing and vaporizing chamber referred to above has been sufficiently heated whereupon the supply of gasolene may be shut off and the supply of kerosene opened, suitable means being provided whereby the supplies of gasolene and kerosene are controlled.

Other features of our invention are hereinafter pointed out.

In the accompanying drawings:—

Figure 1 is an elevation of the upper portion of an internal combustion motor equipped with a carbureter embodying our invention.

Fig. 2 is a central longitudinal sectional view of the exhaust manifold of the engine shown in Fig. 1.

Fig. 3 is an enlarged section on line 3—3 of Fig. 2.

In Fig. 1 of the drawings is shown the upper portion of a four cylinder internal combustion engine, 5 representing the exhaust manifold thereof which is detachably fastened to the cylinders by the usual clamps 6.

The intake manifold of the engine is shown at 7, the upper end thereof connecting as usual with the cylinders and the lower end with a carbureter 8 for gasolene. A throttle 9 is provided as usual in intake 7 just above the carbureter 8.

Extending through the exhaust manifold 5 is a U-shaped length of pipe 10 which constitutes the mixing and vaporizing chamber referred to above. One end of chamber 10 is connected by a pipe 11 with the intake manifold 7 at a point just above the throttle 9 while the opposite end of said chamber is connected by a pipe 12 with a reservoir 13 holding a supply of relatively heavy hydro-carbon such as kerosene. At its junction with chamber 10 the pipe 12 is provided with a needle valve 14 and at a point between said needle valve and reservoir 13 with a stop cock 15.

Adjacent valve 14 the chamber 10 is provided with an air inlet port 16 controlled by an inwardly opening check valve 17 whose stem 18 is threaded and carries an adjustable nut 19 through which a spring 20 acts to yieldingly hold said valve closed on its seat.

During each suction stroke of the engine air is drawn into chamber 10 past valve 17 and at the same time kerosene is drawn into said chamber past needle valve 14 and mixed with the air entering at inlet 16. The needle valve 14 and the discharge orifice 21 of said valve are constructed so as to cause the kerosene to be broken up or atomized as it discharges into chamber 10 thus permitting or insuring thorough intermixing of the air and kerosene. This mixture of air and kerosene is heated during its passage

2
through chamber 10 with the result that the kerosene is thoroughly vaporized and combined with the heated air by the time that the mixture is drawn from the chamber 10 through pipe 11 to the cylinder of the engine.

Stuffing boxes 22 are provided at the four points where the chamber 10 extends through the walls of the exhaust manifold. 10 The engine, when cold, is started with stop cock 15 closed and throttle 9 open and is run on gasoline from carbureter 8 until the manifold 5 and chamber 10 have become heated to the proper degree after which 15 valve 15 is opened and throttle 9 closed.

The proper relative proportions of air and kerosene entering chamber 10 is established by adjustment of valve 14 and nut 19.

The manifold 5 together with the vaporizing and mixing chamber 10 and the parts connected with other than the engine and intake manifold, are herein shown as embodied in an attachment for an engine of a well known make, the only alteration in 25 the construction of the engine required to apply the attachment being to substitute the manifold 5 for the original exhaust manifold of the engine and to make the connection between pipe 11 and intake manifold 7.

30 An internal combustion engine provided with a carbureter constructed in accordance with our invention and using kerosene is more efficient and economical than when gasoline is used and, moreover, when running under proper conditions of adjustment 35 of this attachment the combustion seems to be nearly perfect as there is practically no

trace of carbon observable in the cylinders even after several weeks' use of the motor.

In the pipe 11 is provided a manually operated valve 23 which is closed while the engine is being operated from the gasoline supply and left open while being operated from the kerosene supply.

45

What we claim is:

In combination, a main reservoir for holding a supply of heavy hydro-carbon fuel oil such as kerosene; an exhaust manifold to connect with the exhaust ports of an internal combustion engine; an unobstructed 50 pipe extending through said exhaust manifold heated by the exhaust gases passing through the latter; a definitely restricted air inlet near one end of said pipe; an oil inlet at the same end of said pipe connected 55 with said reservoir; a valve controlling said oil inlet; a second pipe for connecting the opposite end of said first pipe with the intake of the engine, and a manually operated valve in said second pipe, said two inlets 60 supplying air and oil in final proportions to complete the explosive mixture within said first mentioned pipe, and said manually operated valve controlling the delivery of the 65 mixture to the engine without varying the proportions of oil and air.

In testimony whereof we have affixed our signatures.

HARRY PHILIP THATCHER.
